UNITED STATES PATENT OFFICE.

JOHN M. CLARK AND JOHN C. CRUME, OF DAYTON, OHIO.

COMBINATION-TOOL.

SPECIFICATION forming part of Letters Patent No. 760,613, dated May 24, 1904.

Application filed February 13, 1903. Serial No. 143,165. (No model.)

To all whom it may concern:

Be it known that we, JOHN M. CLARK and JOHN C. CRUME, citizens of the United States, residing at Dayton, in the county of Montgomery and State of Ohio, have invented certain new and useful Improvements in Combination-Tools; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention comprises a combination-tool adapted to a variety of uses about the household and elsewhere.

The invention is an improvement of the tool shown and described in Letters Patent No. 692,828, granted to ourselves February 11, 1902.

The present implement combines in a useful form an adjustable wrench that is adapted to be used on articles of varying diameters from the cap of a fruit-jar to an ordinary gas burner or tube for disconnecting or connecting the same. The next useful feature consists of a can-opener which is attached to one member of the wrench in such a manner that it may be placed out of an operative position when not to be used.

Other useful features of the implement consist of a wire-cutter, a knife-sharpener, a cork-screw, means for removing the metallic strip or band from sardine-boxes and other boxes which employ the well-known metal strip or band for uniting the box and cover, a screw-driver, means for removing the sealed cap-stopper from bottles, means for removing crown-caps from bottles, a tack-puller, and, finally, it may be utilized as an ordinary pincher.

Preceding a detail description of the invention, reference is made to the accompanying drawings, of which—

Figure 1 is a side elevation of our improved combination-tool, showing the same adjusted to the maximum limit of the wrench. Fig. 2 is a similar view showing the tool adjusted to its minimum limit. Fig. 3 is a rear edge ele-

vation. Fig. 4 is a detached view of the upper portion of the stationary member. Fig. 5 is a view of the lower edge of the adjustable wrench-jaw.

In a detail description of the invention similar reference characters indicate corresponding parts.

The implement as a whole is stamped from a suitable quality of sheet-steel to obtain both a requisite strength and lightness.

1 designates the stationary member, which contains a longitudinal slot 2' in its body and terminates at its upper end in a wrench-jaw 5, having on its inner side suitable teeth or serrations 6. The extreme end of said jaw is provided with serrations 7, which do not lie in the same circle with the serrations 6. The lower swinging member or wrench-jaw 2, which is adjustable, is also provided with similar serrations 6 and 7. These jaws—that is to say, the adjustable jaw 2—may be placed in a position to engage the cap of an ordinary fruit-jar—such, for example, as a Mason jar or any article of a smaller diameter—while the extreme serrated ends 77 of said jaws may engage any body of much smaller diameter—such, for example, as an ordinary gas-burner—and thus perform the function of gas-pliers.

The swinging member or adjustable jaw 2 is constructed of two sheets or pieces of metal secured together and having their inner ends separated to provide a suitable space 8 to encompass the sides of the stationary member.

1. The extreme outer end of the said lower jaw terminates in a tack-puller 9. The longitudinal slot 2' in the stationary member receives a fulcrum-block 10, to which the inner or bifurcated end of the jaw 2 is pivoted at 11. The slot 2' has two shoulders in it, 12 and 13, on the same side, which are adapted to hold the fulcrum-block 10 in an upper or lower position—in the upper position when the implement is adjusted to its minimum limit, as in Fig. 2, and in the lower position when the implement is adjusted to its maximum or widest position.

14 designates a plate-spring which is suitably confined within the longitudinal slot 2', adjacent to the rear wall thereof, and exerts a constant pressure on the fulcrum-block 10 to

maintain it in contact with the front wall of said slot, as shown in Fig. 4. As before stated, the adjustable jaw 2 is pivoted to the upper end of the fulcrum-block at 11.

- 5 15 designates a handle-carried head-section which operates the movable jaw 2. The upper end of this head-section is bifurcated to encompass the stationary member 1 and is pivoted at 16 to the lower end of the fulcrum-block. It will be seen that by means of this handle 15 the fulcrum-block 10 may be drawn against the spring 14 and dislodged from the upper shoulder 12 and then moved down to the lower limit of said slot, as in Fig. 1, and 10 the spring 14 permitted to engage said fulcrum-block against the lower shoulder 13. For example, if it is desired to change the implement from the diameter of wrench shown in Fig. 2 to that shown in Fig. 1, the handle 15 is drawn outwardly, as in Fig. 1, pulling the fulcrum-block 10 outwardly, and the said handle is then lowered to the position in Fig. 1, carrying the fulcrum-block to the lower limit of the slot.
- 25 17 designates a wire-cutter or edge which is on that portion of the handle-head section 15 which lies immediately below the adjustable jaw, said adjustable jaw combining with the cutter 17, when the implement is in the 30 position shown in Fig. 2, to perform the functions of a wire-cutter. It will be noted that the lower side of the adjustable jaw has a recess 18 therein, which enables the adjacent surface or edge 19 of the handle-head 35 section to enter said recess when the implement is moved to the position shown in Fig. 2, and thereby sever the wire, which has been placed in the space 20 above the cutter 17.
- 21 designates a can-opener or blade which 40 has a curved cutting edge 22 and a bearing shoulder or fulcrum 22', the latter bearing upon the edge of the can, making it possible to cut any diameter of can. This can-opener is pivoted against a side of the handle-head 45 section 15 on the pivot 16 and when lowered to an inoperative position as shown in Fig. 1, has its end confined within a guard 23, which is bent from one side of the handle-head section 15.
- 50 Figs. 2 and 3 show the can-opener in operative positions. It is held in such position by means of a stud or pin 24, projecting from a side of the handle-head section 15, and a projection 25, stamped from one side of the 55 movable jaw 2. This projection or detent 25 being on the movable member or jaw 2 and the pin or projection 24 being on the handle-head section 15 the can-opener or blade 21 is enabled to be moved to the operative position, 60 as shown, as follows: The members 1 and 15 are opened or spread apart, this taking place while the fulcrum-block is in any position. As the said members 1 and 15 are thus being opened the edge *a* of the handle-head section 65 15 coming against the edge *b* of the movable

jaw 2 will cause said jaw to open on its pivot 11 and will thus move the projection 25 back slightly to a position out of the path of the blade 21, and at the same time the members 1 and 15 are thus opened the detent or projection 24 moves slightly downward to form the inner stop for the blade 21. The handle-head section 15 and the movable jaw 2, it will be understood, move on separate pivots 16 and 11 in this operation and impart opposite 75 arc movements to said inner and outer stops 20 and 25. In operating the can-opener the wrench-jaws must be closed, in which event they form a guide which lies on the outer side of the can as the opener is moved around 80 in a circle. Owing to the length of the members 1 and 15 a very considerable leverage is obtained for the can-opener, and the operation of opening a can is thereby made very 85 easy. The lower portion of the handle, 85 which carries the head 15, is curved throughout its length to provide a suitable housing 26 for the corkscrew 27 when the latter is not in use. The said corkscrew is pivoted between the sides of the handle at 28 and is moved 90 downwardly, as in Fig. 1, when its use is desired. When not in use, it is confined within the handle, as in Figs. 2 and 3.

29 is a screw-driver projecting from the extreme end of the handle opposite the head-section 15 in a position to not interfere with the operation of the corkscrew.

30 is a slot in the extreme end of the handle adapted to receive the end of a metallic strip, such as is used to seal cans containing various 100 articles. The end of the strip is secured to said slot in a manner similar to the use of the usual key which accompanies cans or packages of this character. The work of removing such strip by means of this implement is 105 much easier than with the small key heretofore employed.

31 designates a knife-sharpener which is secured to the handle 15. The sharpening edge 32 thereof is on a suitable angle to permit of a 110 knife being drawn between said edge and the handle. The extreme end of the stationary member 1 is provided with a projection or hook 35, which is adapted to be placed under the wire seal usually employed on beer and ale 115 bottles. By means of this hook or projection the wire fasteners used to prevent the accidental removal of corks may be easily broken. The extreme end of said member 1 is stamped out to provide an opening 33, which permits of the use of the projection 34 in removing the metallic crown-caps from bottles. These caps are usually maintained on the mouth of bottles by fluting or corrugating the surrounding edges. In employing this implement to remove such caps a portion of the cap enters the opening 33, so as to permit the working edge 34 of the implement to reach below the fluted or corrugated edge of the cap. After this is accomplished the implement is raised up by the 125 130

force of the hand, and the cap is thereby easily removed.

Having described our invention, we claim—

1. In a tool of the class described, the combination of a stationary member, a swinging member having a shiftable fulcrum mounted upon the stationary member and presenting a cutting edge, and a handle carrying a head-section having a separate pivotal mounting upon the shiftable fulcrum for the swinging member, said head-section bearing a cutter having a cutting action in connection with the swinging member when the handle is moved in a direction for closing the latter.
- 15 2. In a tool of the class described, a stationary member, a swinging member having a shiftable fulcrum mounted upon the stationary member and provided with a notched or recessed cutting edge, and a handle provided with a head-section having a separate pivotal mounting upon the shiftable fulcrum for the swinging member, said head - section being adapted to work into the recess or notch of

the swinging member and also bearing a cutter having a slidble movement with reference to the cutting edge of the swinging member for cutting purposes.

3. In a tool of the class described, a stationary member, a swinging member having a pivotal mounting on the stationary member and provided with an offset catch projection, a handle carrying a head-section arranged below the swinging member and also provided with an offset stop projection, and a swinging shouldered blade having a pivotal support on the said head-section and arranged to be carried to a position between and against said catch and stop projections carried respectively by the swinging member and head-section.

In testimony whereof we affix our signatures in presence of two witnesses.

JOHN M. CLARK.
